ALKYL CRESOLS

George W. Raiziss and Le Roy W. Clemence,
Philadelphia, Pa., assignors to Abbott Laboratories,
North Chicago, Ill., a corporation of
Illinois

No Drawing. Application June 22, 1934, Serial
No. 731,898

2 Claims. (Cl. 260—154)

Our invention relates to a group of compounds which have bactericidal and bacteriostatic value, and may be classed as alkyl cresols. They are also of value as intermediates for halogenated alkyl cresols which also have bactericidal and bacteriostatic value, which halogenated compounds are described and claimed in certain of our co-pending applications.

It is known that the germicidal value of chemical compounds is generally greatly reduced in the presence of blood serum or whole blood. The compounds which we have discovered and which form the subject-matter of this application are of high germicidal value in the presence of blood serum and at the same time are of low toxicity, so that our new compounds can be introduced into the human body in relatively high concentrations without any deleterious effect to the patient.

Our new compounds which are specifically described herein, comprise the 2-methyl-butyl, tertiary amyl, 1-methyl butyl, and 1-ethyl propyl derivatives of ortho, meta, and para cresols. All of these compounds may be made by substantially the same process as is described in co-pending application of one of us, Raiziss application Serial No. 643,521, filed November 19, 1932. Said method is essentially as follows:

204 grams of zinc chloride are dissolved with heating and mixing in 132 grams of the particular alcohol, depending upon the alkyl group which it is desired to introduce into the cresol nucleus, say, 2-methyl-butyl alcohol. The temperature is raised to the appropriate reaction temperature set forth below; in the case of 2-methyl-butyl-ortho-cresol this would be 165—170° C. 108 grams of the desired cresol, ortho-cresol in this case, are then added gradually. After the addition is complete the temperature is maintained until the mixture separates into two layers and is then continued for about one hour until a maximum separation occurs. The mixture is then cooled and poured into two liters of water containing a small amount of HCl. The oily layer which separates is then washed with water several times, and is extracted with three portions of 10 per cent NaOH (about 300 cc. in each portion). The alkaline extract is allowed to stand until there is a clear separation of the insoluble oil. This is removed by extraction with petroleum ether until the alkaline layer no longer becomes cloudy on diluting a small sample with water. The alkaline portion is drawn off and then acidified with HCl. The oil which is liberated is separated, washed with water and then distilled in vacuo. The desired fraction is collected at the boiling points set forth below; in the case of 2-methyl-butyl-ortho-cresol, the desired product would be collected at 134—135° C. at 10 mm. pressure and has a specific gravity of 0.973.

60 The various other products are obtained by

the same procedure, substituting the appropriate alcohol and cresol, according to the product desired.

All of the compounds disclosed herein are substantially colorless oils, soluble in organic solvents and in dilute alkalies, and insoluble in water.

The physical properties of the compounds which we have prepared are as follows:

No.	Compound	B. P.	Press.	Sp. gr.	Max. reaction temp.	10
(1)	(1-methyl-butyl)-ortho-cresol.	128-127°	8 mm.	0.970	165°	15
(2)	(1-methyl-butyl)-meta-cresol.	139-145°	13 mm.	0.978	165°	
(3)	(1-methyl-butyl)-para-cresol.	136-144°	12 mm.	0.970	165°	
(4)	(2-methyl-butyl)-ortho-cresol.	134-135°	10 mm.	0.973	165-170°	
(5)	(2-methyl-butyl)-meta-cresol.	138-144°	9 mm.	0.970	165°	20
(6)	(2-methyl-butyl)-para-cresol.	142-150°	16 mm.	0.980	165-170°	
(7)	(1-ethyl-propyl)-ortho-cresol.	134-138°	10 mm.	0.987	140°	
(8)	(1-ethyl-propyl)-meta-cresol.	138-145°	10 mm.	0.970	140°	25
(9)	(1-ethyl-propyl)-para-cresol.	125-143°	10 mm.	0.984	150°	
(10)	Tertiary-amyl-ortho-cresol.	135-137°	10 mm.	0.973	140°	
(11)	Tertiary-amyl-meta-cresol.	137-140°	11 mm.	0.973	140°	
(12)	Tertiary-amyl-para-cresol.	134-141°	10 mm.	0.992	135°	30

The above compounds have the following graphic formulas:

(7)

(1-ethyl-propyl)-ortho-cresol.

(8)

(1-ethyl-propyl)-meta-cresol.

(11)

Tertiary-amyl-meta-cresol.

(12)

Tertiary-amyl-para-cresol.

5

10 (9)

(1-ethyl-propyl)-para-cresol.

(10)

Tertiary-amyl-ortho-cresol.

We claim as our invention:

1. A cresol derivative having the formula:

10

2. As a germicide, α ethyl-propyl ortho-cresol. 15GEORGE W. RAIZISS.
LE ROY W. CLEMENCE.
